UNITED STATES PATENT OFFICE.

CHARLES A. LUNDGREN, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,033,109.

Specification of Letters Patent. Patented July 23, 1912.

Application filed October 20, 1910. Serial No. 588,089.

To all whom it may concern:

Be it known that I, CHARLES A. LUNDGREN, a citizen of the United States, residing at Detroit, in the county of Wayne and State of Michigan, have invented certain new and useful Improvements in Adding-Machines, of which the following is a specification.

The object of the present invention is to provide an attachment to or equipment for adding machines which will facilitate "repeat" operations as performed for purposes of multiplication and division.

It will be understood that adding machines are commonly equipped with a so-called "repeat" key and that it is customary to perform multiplication by setting up on the keyboard the multiplicand and operating such repeat key so as to prevent the automatic release and restoration of amount keys which ordinarily takes place at the conclusion of an adding operation, the machine being then operated a number of times corresponding with a digit of the multiplier. In such use of the ordinary adding machine it is necessary for the user to keep count of the operations of the machine and this is apt to lead to mistakes through a mis-count. By the present invention the user is relieved of the mental work of keeping count of operations for it is rendered possible to set the machine for the requisite number of repeat operations and have a discontinuance take place automatically. Thus in the case of a motor driven machine the user can manipulate to set a controlling device at an indexed position denoting the requisite number of repeat operations and by said act not only render the repeat mechanism effective as in the case of the operation of the familiar repeat key, but also provide for continued effectiveness of such mechanism during that number of operations of the machine. Then by touching off the starting bar as in the use of familiar motor equipped adding machines, the machine will be set in operation and caused to operate again and again while the amount keys originally depressed remain depressed whereby the same amount is repeatedly added until the adding operations equal the units of the multiplier digit whereupon the repeat mechanism is automatically released and restored to normal.

In the drawings which accompany and form part of this specification Figure 1 represents in right side elevation a sufficient portion of an adding machine of the well known Burroughs type to illustrate incorporation therein of devices for carrying out the present invention, all parts being here shown at normal; Fig. 1^a is a detail sectional view of key-releasing and restoring devices of the machine; Fig. 2 is an enlarged elevation showing some of the parts which similarly appear in Fig. 1 on a smaller scale; Fig. 2^a is a detail cross section taken on the line 2^a—2^a of Fig. 2; Fig. 3 is a view quite similar to Fig. 2 though otherwise sectionalized and showing a changed relation of parts resulting from the setting of the repeat devices and a partial operation of the machine; Fig. 4 is a fragmentary top plan view of the machine.

Reference may be had to Burroughs Patent No. 504,963 of September 12, 1893, Pike Patent No. 615,895 of December 13, 1898, Vincent Patent No. 866,750 of September 27, 1907 and Burd Patent No. 963,087 of October 5, 1909, for various particulars of the Burroughs machine as now familiarly known on the market.

The invention is preferably shown adapted to the electric drive machine shown in said Vincent patent though it is not to be understood as limited to use with a power driven machine. In view of the disclosure in said Vincent patent it will not be necessary here to describe in detail the complete electric equipment, and in view of the disclosures in this and other prior patents above mentioned it will not be necessary to extend the description to the particulars of the machine proper, though certain familiar parts will be designated herein-after in order to make clear the coöperation therewith of the added devices of the present invention.

The electric motor is designated by the numeral 37, and the clutch mechanism through which it drives the machine is designated in a general way by the numeral 36. The usual starting bar located at the right of the amount keys is designated by the numeral 360 and it will be understood that depression of this starting bar effects a closing of the clutch in the manner described in said Vincent patent, such closing of the

clutch resulting in forward oscillation of the familiar full stroke sector 311 which as usual is secured to a short rock shaft 300.

The numeral 291 designates the usual depressible amount keys which operate upon small bell cranks 217 to set stop wires 270 for regulating the movement of the adding racks 610. Each row of bell cranks 217 has the usual detent slide 214 adapted to be 10 thrust rearward upon depression of a key and detained by the detent pawl 228. The latter is as usual adapted to be released by the cross rod 202 of an oscillatory bail such cross rod also acting against the end of the 15 slide strip. The right hand side piece 219 of said bail carries the usual roller stud 262 arranged to be acted upon by the wiper piece 623 carried by a three-armed rocker plate 622 the depending arm of which is 20 normally engaged by a shoulder of the full stroke sector 311 as shown in Fig. 1, so that the plate is held back against the stress of the spring 618.

It will be understood that the customary mode of effecting repeat operations is to 25 depress a key which interposes an obstruction in the path of the plate 622 so that its spring 618 is prevented from carrying the wiper piece 623 down past the roller stud 262 and hence there ensues no forward 30 rocking of the bail rod 202 to release and restore the amount key stop devices. In the present instance an arm 218 loose upon the cross rod 200 is adapted to be swung upwardly into the path of a stud *a* on the 35 rocker plate 622 for the purpose of effecting this familiar result and this may be accomplished by depression of a repeat key R, but for the purposes of the present invention said arm is also adapted to be moved 40 to effective position by a slide bar A suitably guided for forward and backward movement between the keyboard plates 213 and 212. The said arm 218 has a portion extending 45 considerably forward of the cross rod 200 and is notched at *b* adjacent said rod, the said slide bar having a depending lug with a roller stud *a'* normally occupying said notch. The slide is normally rearward 50 and when moved forward said roller stud acts with a camming effect upon the forward side of the notch thereby rocking the arm 218 to effective position said arm being normally held out of such position by a 55 spring 218^a connecting its forward extremity to a portion of the framework. The forward portion of the arm 218 is sufficiently elongated to provide for varying adjustments of the slide bar in each of which 60 the arm will be held displaced or in effective position, the purpose being to provide for as many different adjustments of said slide bar as units of a multiplier digit might require. This would mean eight different 65 positions of the slide bar in each of which

it should hold the arm 218 in effective position. The upper edge of the bar A for a distance at its forward portion is notched or ratcheted to provide a series of shoulders *a*² by which to advance the bar varying distances, and for indexing purposes the several inclined surfaces adjacent said shoulders are inscribed with numerals from 2 to 9 as illustrated in Fig. 4. A guide plate A' is mounted upon the keyboard plate 213 and is constructed to accommodate the slide bar A and apertured to normally expose all of said numerals as illustrated in Fig. 4. This cover plate has a slotted rear portion in which is mounted a finger piece A² for setting the bar A. The latter is normally held rearward by a spring A³ and the finger piece is adapted to be engaged with any one of the shoulders *a*² and drawn forward to advance the slide bar against the stress of the latter's spring. To provide for the proper manipulation of the finger piece it is provided at its rear end with pivot pins *a*³ engaging under flanges of the cover plate A' and slidable below the same so that the finger piece may have both a pivotal movement up and down and sliding movement forward and back. It is limited as to pivotal movement by a cross piece *a*⁴ extending between ears of the cover plate A'. The finger piece has at its forward end an upstanding portion *a*⁶ by which to grasp it and below and a little forward of this upstanding portion the finger piece is formed as a pawl or dog *a'* for engaging the shoulders *a*². Normally this pawl or dog rests upon the rear portion of the inclined surface of the slide bar A in rear of the rear-most shoulder *a*², as illustrated in Fig. 2. The finger piece may be lifted and drawn forward for engagement with any one of the said shoulders *a*² and then engaged therewith and drawn farther forward to carry with it the slide bar A, the movement being limited by abutment of the dog or pawl against a shoulder *a*⁸ of the cover plate A' which shoulder defines the forward end of the aperture through which the multiplier numerals on the slide bar show. The finger piece is connected by a strap or ribbon A⁴ with a spring A⁵, Fig. 1, for returning it to and holding it in normal position. When it has been operated to set the slide A it is released and said spring will bring it back; its rearward movement being limited by abutment of a vertical shoulder *a*⁹ against the end of the slot in the cover plate A'. The slide bar A has an incline *a*¹⁰ back of the notched or ratcheted portion in its upper edge so that when said slide bar thereafter returns to normal the pawl or dog *a'* may be brought to the normal position before defined.

The slide bar A is returned to normal step by step in successive operations of the ma-

chine and in this manner the number of repeat operations is automatically controlled or determined according to the extent to which the bar has been advanced through the use of the finger piece A' after the manner above described. To this end the underside of the bar is notched or ratcheted to provide an escapement rack A⁶, and a pallet is provided for engaging with said rack. 5 One member of said pallet is in the form of a detent D pivoted upon a cross rod 201 and normally engaged with the rack A⁶ by a spring d which connects it with the other member D' of the pallet, said other member 10 being also pivoted upon the cross rod 201 and having a laterally projecting stud d' overlying the member D. It also has a depending arm D² connected by a spring D³ to a part of the machine frame. Said depending arm D² has a roller stud d² normally engaged by a finger d⁸ of the rocker plate 622 as illustrated in Fig. 2 so that the pallet member D' is normally held disengaged from the rack A⁶ as shown in Fig. 2. 15 When the slide bar A is moved forward one or more of the teeth of the rack will be carried forward over the member D which will operate as a detent to temporarily detain the slide bar A against the stress of the spring A³ so that the arm 218 will be held at effective position to obstruct the rocker plate 622. The limited movement which the latter has under such circumstances is sufficient however to operate the escapement device, the 20 finger d⁸ retreating far enough to permit the spring D³ to swing the escapement member D' in the path of the shoulder of the rack A⁶, and withdraw the member D from engagement with the rack as illustrated in Fig. 25. Thereafter when the rocker plate is returned to normal by the full stroke sector 311 the escapement pallet is rocked the other way to disengage the member D' from the rack and reengage the member D with the 30 rack. It will be obvious that this provides for a step by step return of the slide bar A which will finally bring its roller stud d' back to the notch b and permit the spring 35 218⁴ to restore the arm 218 to normal so that in the ensuing operation of the machine the amount stop devices will be released and the amount keys restored. 40

It will be obvious that the above described mechanism provides a ready means for automatically determining the number of operations to be performed when repeated addition is desired for the purposes of multiplication, the user being relieved all together of the work of mentally keeping track of the 45 number of times the machine is operated.

It is desirable with a motor driven machine to also relieve the user of the necessity of holding down the starting bar during the successive operations, and the present invention provides for detaining that bar under

control of the above described repeat devices. To this end the lever 361 which forms part of the familiar starting mechanism has a stud e which normally engages a cam surface e' below a notch e² in a detent slide bar E guided upon the cross rod or shaft 200 and the cross shaft 801 and held rearward by a spring e³. When the starting member is depressed and the lever 361 rocked the stud e is forced up past the cam edge and 70 becomes seated in the notch e² so that the starting connections are held in operative condition. At its rear end the detent bar E has a finger e⁴ which confronts a stud e⁵ carried by the side bar 219 of the key releasing 75 and restoring bail. Therefore whenever that bail is swung forward as to its upper portion the detent bar will be thrust forward so as to release the starting connections. In the case of an operation which is to be repeated the bail does not swing forward consequently said connections remain set, but with the last of a series of repeat operations the bail is operated and consequently the starting connections will be released. 80

It has been before stated that provision is made for the ordinary repeat adjustments by depression of a key. In the present instance that key, designated R, has a lug r engaging over a stud r' on the forward extension of the arm 218, and the key is pivotally mounted on the forward end of an arm G pivoted upon the cross rod or shaft 200 and upheld by a spring g. 90

It is customary to provide for rocking the key releasing and restoring bail whenever desired to correct errors and there is here shown a key C such as commonly employed for this purpose though it is located a little differently than usual. Its stem C' is bifurcated to embrace a stud upon an upwardly projecting extension of the bail, the key being located at the rear of the keyboard instead of at the middle right-hand portion of the same, the latter portion being in the present instance occupied by the finger piece A'. 100

What I claim is:

1. In a machine of the character described, the combination with a prime mover, accounting elements adapted to be operated thereby, manipulative amount-determining devices adapted when set to supply fixed stops for said accounting elements, detent means adapted to hold said devices set and means for releasing the amount-determining devices from the detent means; of means for disabling the releasing means, and controlling devices adapted to automatically reenable said releasing means in a predetermined number of successive operations of the prime mover. 115

2. In a machine of the character described, the combination with a prime mover, accounting elements adapted to be operated 120

125

thereby, manipulative amount-determining devices adapted when set to supply fixed stops for said accounting elements, detent means adapted to hold said devices set and means for releasing the amount-determining devices from the detent means, including a member reciprocated by the prime mover; of means for interfering with the action of said member, and means for 10 moving the interference in a predetermined number of operations of the prime mover.

3. In a machine of the character described, the combination with a motor-driven prime mover, a manipulative motor-controller, manipulative amount-determining devices, 15 detent means therefor, and detent releasing means; of means for disabling the latter, means for detaining the motor-controller, and controlling devices adapted to automatically reenable said releasing means and disable the motor-controller detaining means.

4. In a machine of the character described, the combination with a motor-driven prime mover, a manipulative motor-controller, manipulative amount-determining devices, 25 detent means therefor, and detent releasing means; of means for disabling the latter, means for detaining the motor-controller, and controlling devices adapted to automatically 30 reenable said releasing means the latter adapted in turn to disable the motor-controller detaining means.

5. In machine of the character described, the combination with a prime mover, manipulative amount-determining devices, detent means therefor, and detent releasing means including a member adapted to normally receive full reciprocation from the prime mover; of means for limiting at will 35 the extent of reciprocation of said member, and escapement devices operated by the latter in its limited reciprocation and adapted to disable the limiting means in a predetermined number of operations of the prime 40 mover.

6. In a machine of the character described, the combination with a prime mover, manipulative amount-determining devices, detent means therefor, and detent releasing means including a reciprocable member 45 spring-actuated one way and impelled contra by said prime mover; a movable abutment piece adapted when moved from normal to obstruct said reciprocable member and limit its movement; a spring-held member adapted when moved from normal to cam said abutment piece into effective position; and an escapement device engaging said spring-held member, and adapted to detain it at 50 different positions, said escapement device being actuated by said reciprocable member to effect its step by step return to normal in successive operations of the prime mover.

7. In a machine of the character described, the combination with a prime mover,

manipulative amount-determining devices, detent means therefor, and detent releasing means including a rocking member spring-actuated one way and impelled contra by said prime mover; a movable abutment piece adapted when moved from normal to obstruct said rocking member and limit its oscillation; a spring-held slide adapted when moved from normal to cam said abutment piece into effective position; and an escapement device engaging said slide and adapted to detain it at different positions, said escapement device being actuated by said rocking member to effect its step by step return to normal in successive operations of the prime mover. 70

8. In a machine of the character described, the combination with a prime mover, manipulative amount-determining devices, detent means therefor, and detent releasing means including a rocking member spring-actuated one way and impelled contra by said prime mover; a movable abutment piece adapted when moved from normal to obstruct said rocking member and limit its oscillation; a spring-held ratcheted slide adapted when moved from normal to cam said abutment piece into effective position; and an escapement pallet, composed of independently pivoted members spring-connected whereby one is normally engaged with said ratcheted slide, the other pallet member being rotatively engaged with the first and spring-drawn to disengage the same from the slide but being normally retracted by engagement with the aforesaid rocking member of the releasing and restoring means. 80

9. In a machine of the character described, the combination with a prime mover, manipulative amount-determining devices, detent means, and detent releasing means including a rocking member spring-actuated one way and impelled contra by said prime mover; a movable abutment piece adapted when moved from normal to obstruct said rocking member and limits its oscillation; a spring-held slide adapted when moved from normal to cam said abutment piece into effective position and having a series of index shoulders; a slide-setting dog pivotally and slidably mounted for engagement with one or another of said shoulders and for movement varying distances with the slide; and an escapement device engaging said slide and adapted to detain it at different positions, said escapement device being actuated by said rocking member, to effect its step by step return to normal in successive operations to the prime mover. 105

10. In a machine of the character described, the combination with a prime mover, manipulative amount-determining devices, detent means, and detent releasing means including a rocking member spring- 110

- actuated one way and impelled contra by said prime mover; a movable abutment piece adapted when moved from normal to obstruct said rocking member and limit its oscillation; a spring-held slide adapted when moved from normal to cam said abutment piece into effective position and having a series of index shoulders; a slide-setting dog pivotally and slidably mounted for engagement with one or another of said shoulders and for movement varying distances with the slide; a spring and connections for retracting said dog; and an escapement device engaging said slide and adapted to detain it at different positions, said escapement device being actuated by said rocking member to effect its step by step return to normal in successive operations of the prime mover.
11. In a machine of the character described, the combination with a prime mover, manipulative amount-determining devices, detent means therefor, and detent releasing means including a rocking member spring-actuated one way and impelled contra by said prime mover; a motor for driving the prime mover; motor-controlling means including a movable member having a stud; and a detent adapted to engage said stud and be displaced by the aforesaid rocking member.
12. In a machine of the character described, the combination with a prime mover, manipulative amount-determining devices, detent means therefor, and detent releasing means including a rocking member spring-actuated one way and impelled contra by said prime mover; a motor for driving the prime mover; motor-controlling means including a movable member having a stud; a detent adapted to engage said stud and be displaced by the aforesaid rocking member; a second rocking member spring-actuated one way and impelled the other way by the prime mover; an abutment piece for obstructing spring movement of said second rocking member; a differentially adjustable spring-held member for setting said abutment piece; and escapement devices for effecting step by step return of said adjustable member under actuation by said second rocking member.
